UNITED STATES PATENT OFFICE

2,616,388

TRAFFIC SIGNAL

Herbert B. Mueller, Los Angeles, Calif.

Application April 2, 1946, Serial No. 658,893

20 Claims. (Cl. 116—63)

1

My invention relates to a traffic signal and has for its principal object to provide a signal designed to be placed at the intersection of streets and highways to provide a warning to pedestrians as well as to drivers of vehicles when they may cross the intersection in safety.

The principal object of my invention is to provide means in a traffic control signal, that will make it possible for the pedestrian and motorist to use his or her God given judgment as to when he or she may cross an intersection in safety.

Another object of my invention is to change the mental attitude of the pedestrian and motorist from uncertainty, danger and confusion to certainty, safety and serenity, by displaying both "Red" and "Green" light in one panel at the same time and the use of an indicator constantly moving across one color and into the opposing color to indicate an impending change of the signal.

Another object of my invention is to maintain a steady flow of traffic at an intersection by the use of only one signal, with one light source and a constantly moving indicator clearly visible in four directions day or night and thereby give positive warning to all persons at one and the same time, of an approaching change.

A feature of my invention is, to provide a wider portion of each end of the "Red" or "Stop" light panel with the opposing color of green, and the "Green" or "Go" light panel with the opposing color of red, preceded by a color of caution if desired. In this way, the pedestrian or driver of a vehicle, after having noted the indicator moving on a panel of red or green toward the opposing color of green or red will have impressed on his mind the exact time of the on coming change; and as a result, his mind and eyes will be free to concentrate on the unknown acts of other motorists, or pedestrians, instead of the usual unknown time of change in a conventional traffic signal.

Another feature of my invention is the moving time indicator or control member which may be a circular lighted or unlighted dark band or preferable an arrangement of reflectors using the light from the panel over which it travels and reflecting it to two sides and forward, the reflectors causing a dark area in front of the light panel and light on either side consisting of its own background.

Another feature of my invention is in the regularly spaced lateral extensions in the light panels which are useful to the pedestrian or motorist as a gauge or scale so he can tell instantly, after having noted the direction of the moving indicator, the elapsed time and the time left before a change in each cycle, and he will then be able to use his own judgement whether to cross or not to cross an intersection.

2

The accompanying drawings illustrate the invention.

Figure 1 is a diagrammatic elevational view partly in section of the invention.

Fig. 2 is a fragmental detail showing how the illumination control member or gauge is fixed to the cables.

Fig. 3 is a plan view partly in horizontal section on line 3—3 of Fig. 1 showing the location of the locking dogs and spring mechanism for operating the light control cylinder with parts broken away to show interior construction.

Fig. 4 is a fragmental detail view showing how the roller releases one of the dogs.

Fig. 5 is an enlarged fragmental exaggerated perspective detail view that shows the spring mechanism and also shows the engagement of the ends of the springs with the tension producing pins.

Fig. 6 is a sectional view analogous to Fig. 3 on the line 6—6 of Fig. 1, showing the top driving drum and how the pulley cables are fixed thereto and also shows location of the shields and light tubes or bulbs.

Fig. 7 is a small diagrammatic plan view of the moving illumination control member or gauge.

Fig. 8 is a side elevation of Fig. 7.

Fig. 9 is a side elevation showing the light control cylinder and showing the red color.

Fig. 10 is a view analogous to Fig. 9 showing the arrangement of the red and green colors.

Fig. 11 is a plan view on a small scale of the oppositely arranged spiral springs which function to impart intermittent reverse rotary motion to the light control cylinder.

It is understood that the traffic signal may be made in different shapes and sizes and various parts of the invention may be constructed without departing from the spirit of the invention; but the form shown is at present deemed most desirable for easy and cheap construction and ready interchange of parts.

The invention comprises a housing 10 having a top 11, and bottom 12 and is provided with upright members 13 and outwardly extending fins or shields 14.

Enclosed in the housing 10 are the oscillating light control cylinder 15 that is rotatably mounted on a shaft 18 and an upper driving drum 16 and lower driving drum 17 that are mounted on the vertical shaft 18 that is mounted in the bearing 19 at the bottom 12 of the housing and extends upwardly through the top bearing 20 to a conventional reduction gearing and reversing gear 21 that is operated by a motor 22 as shown in Fig. 1 of the drawings.

A moving illumination control indicator or gauge member 23 encircles the light control cylinder 15 and is raised and lowered through the annular space between the cylinder 15 and side

wall of housing 10 by cables 24 over the pulleys 25 operable through the driving drums 16 and 17 when the shaft 18 is rotated by the driving mechanism 21 and 22 in timing with the cylinder 15.

The oscillating light control cylinder 15 is so constructed and arranged so as to display red and green colors as shown in Figs. 9 and 10 of the drawings and is composed of one or more parts or pieces of clear or colored transparent material such as glass or sheet plastics and those vertical areas between the colored portions of the wall of said cylinder may be clear, translucent or opaque.

Cylinder 15 has two windows colored red 15a disposed 180 degrees apart and colored green also two windows 15b, 180 degrees apart. At the top and bottom of the red window are short horizontally disposed portions 15c colored green and sumptuary at the top and bottom of windows 15b are short horizontally disposed portions 15d colored red.

Lateral sections 15e of the colors red and green equally spaced as shown in Figs. 9 and 10 of the drawing and the vertical extension 15f of 25 red color cooperate with the traveling gauge or indicator member 23 to indicate the proximate lapse of time until the signal changes from red to green or vice versa.

Mounted in the light control cylinder 15 are 30 illuminated tubes or bulbs 26 that are arranged in the desired position to provide the required light at all times and are connected to a suitable source of current not shown by conventional wiring and contacts known to the art.

Referring to Figs. 3 and 11, a spring mechanism 27 is shown that comprises a top spring 28 and lower spring 29 that are operated by the top driving drum 16 to oscillate the light control cylinder 15 to the right and left by 40 releasing both locking dogs 30 through the roller 31 releasing one dog and then the other intermittently.

The light control cylinder is held in position by the stops 32 that contact the dog brackets 45 33 as shown.

As indicated in Fig. 5 a stationary pin 34 being secured to the web 34a or arm of a spider located inside the top end of the cylinder 15 and is rotatably mounted on the shaft 18 similar to spider 36 holds the spring ends in position and pin 35 depending from the spider arm 36 that is operated by drum 16 through spider arm 36 to wind the springs 28 and 29 to the right or left as shown in broken lines as at X and Z, Fig. 3 of the drawing. The springs 28 and 29 are provided at their opposite ends with hooks ends 28a and 29a that fit into a tubing 34b that is welded to the hub of the web 34a.

The locking dogs 30 are provided with a tension spring 37 that tends to hold the dogs in latched position with the latch 33 and are released by the roller 31 striking the projection 39 of the dogs 30 that are pivoted at 40 to the dog brackets 33 as shown in Figs. 3 and 4 of the drawings.

The traveling gauge 23 is constructed of an upper ring member 41 and lower ring member 42 provided with a plurality of deflectors 43 and reflectors 44 interposed between the ring members and so constructed and arranged to receive light from the windows of the cylinder 15 and divergently reflecting rays of light from the windows as shown in broken lines in Fig. 7 of the drawings.

The spider 36 is fixably mounted to the shaft

18 and is an integral part of the driving drum 16, and the reversely displaced springs 28 and 29 that are tensioned by the shaft 18 and drum operating means 21 and 22 on top of the top plate 11 to cause the light cylinder 15 to turn with a snap on each change of signal.

It is to be understood that in my improved signal, the driving motor operates continuously, that the cylinder having the colored windows 10 rotates periodically for approximately 180 degrees, first in one direction and then in the other so as to alternately display the red and green (stop and go) signals to traffic on the crossing streets and that the gauge ring or reflecting member that travels vertically upon said cylinder, moves continuously, first in one direction and then in the reverse direction.

Thus the signal being illuminated and having the continuously moving light ray reflecting ring, naturally attracts the attention of approaching drivers and pedestrians and by noting the direction of travel of the ring and its proximity to the ends of the illuminated cylinder, they will know definitely whether or not they have sufficient time to safely cross the intersection or that they should await the change of the signal to "Go." A vehicle driver or pedestrian approaching a crossing equipped with the signal, observes the red or green color, also the position of the indicator and control ring 23 relative to the lighted window, and is thus warned whether or not to proceed or stop.

If the indicator ring is moving upwardly through the lower portion of the window or downwardly through the upper portion of said window, the observer knows he has ample time to proceed, but when the ring reaches and passes the laterally disposed extensions 15e, which are in effect caution or warning signals, the observer is warned that a signal change will shortly take place. Vertical extensions 15f at the ends of the windows 15b in cooperation with ring 23, are effective in giving further warning as to an impending signal change.

The speed of the motor driven gearing 21, the tensioning of the springs 28 and 29 and the travel of ring 23, are regulated and co-related, so that there is a short interval of time, one second more or less, between the release of the light cylinder 15 holding means and the starting of ring 23 from the short periods of stop at the ends of its travel.

Thus the animation resulting from the combination of the constantly illuminated windows and the reflecting ring or gauge constantly traveling across said windows, provides an extremely valuable and advantageous safety factor for the control of traffic and prevention of accidents at intersections.

My improved signals may be installed at intersections along a boulevard or arterial highway and set for successive operation, so as to progressively function and thereby enable vehicles to be driven at lawful speed on the highway for considerable distance, without stopping.

Thus it will be seen that I have provided a traffic signal that is simple in construction, positive in operation, inexpensive of manufacture and very effective in performing the functions for which it is intended.

I claim:

1. In a traffic signal a housing having top and bottom plates, bearings on said plates, a vertical shaft journaled in said bearings; an oscillating cylinder and an upper and lower drum mounted on said shaft; said cylinder having two sets of

differently colored windows; means mounted on top of said top plate of the housing to operate said shaft and drums; reversely displaced springs for alternately rotating said cylinder in opposite directions, which springs are tensioned by the shaft and drum operating means on top of said top plate; an illumination control gauge that encircles said oscillating cylinder and means operable by said drums to raise and lower said control gauge to regulate the timing of the changes of the differently colored light passing through said windows.

2. The combination as set forth in claim 1 and the windows of said cylinder having short spaced guide portions extending laterally from their vertical edges, means within said cylinder for illuminating said windows and pairs of inclined reflectors carried by said control gauge for directing light rays radially outward from said gauge.

3. In a traffic signal, a vertically disposed oscillatory cylinder having two sets of differently colored windows, each including short longitudinally spaced guiding portions extending laterally from both sides, means for illuminating said windows, means for periodically partially rotating said cylinder alternately in opposite directions and a constantly moving gauge member arranged to move at predetermined speed across said windows, first in one direction and then in the other.

4. A traffic signal the combination as set forth in claim 3, with means on said gauge member for receiving and divergently reflecting rays of light from said windows.

5. A traffic signal the combination as set forth in claim 3 and which windows are provided with lateral warning signal extensions at both ends.

6. In a traffic signal an oscillating cylinder mounted to rotate on a vertical axis and having a pair of red windows and a pair of green windows, portions of said windows at the upper and lower ends thereof being distinctively colored, means for imparting periodic oscillatory motion to said cylinder, a gauge ring arranged to travel vertically upon said cylinder, means cooperating with the cylinder oscillating means for moving said ring vertically while the cylinder is at rest and reflectors carried by said ring for divergently reflecting the colored rays of light emanating from said windows and from the distinctively colored end portions thereof.

7. In a traffic signal a revolvably mounted member having pairs of spaced windows graduated lengthwise, one pair of windows being distinctively colored relative to the color of the other pair, with portions of said windows at both ends of one pair colored to correspond with the color of the intermediate portions of the other pair of said windows, an indicator ring mounted to move lengthwise of the windows in said revolvably member, means for imparting intermittent oscillatory motion to said member and means for moving said indicator ring lengthwise of said member and its windows while same is at rest.

8. A traffic signal the combination as set forth in claim 7 and having means within said revolvably member for illuminating same and said indicator ring.

9. In a traffic signal, a light panel graduated lengthwise by lateral extensions, an indicator mounted for constant travel across said light panel so as to successively cover said lateral extensions and means for imparting reciprocatory

motion to said indicator lengthwise of said light panel.

10. The traffic signal as set forth in claim 9 with reflectors carried by said indicator for reflecting light rays outwardly and laterally therefrom.

11. In a traffic signal, a longitudinally graduated light panel having distinctively colored end portions, an indicator mounted to move lengthwise of said panel and to enter said distinctively colored end portions at the ends of its travel, means for imparting reciprocatory movement to said indicator at the ends of its reciprocation movements.

15. 12. A traffic signal the combination as set forth in claim 11 and which indicator is illuminated.

13. A traffic signal the combination as set forth in claim 11, and light ray reflecting means carried by said indicator.

20. 14. In a traffic signal, a housing, a shaft mounted for rotation within said housing, driving means for said shaft, a light cylinder rotatably mounted on said shaft, means actuated by said shaft for imparting intermittent oscillatory motion to said cylinder and means for engaging and holding said cylinder against rotation during rotation of said shaft.

25. 15. The traffic signal as set forth in claim 14, with driving drums mounted on said shaft above and below said light cylinder, a pair of reversely arranged springs associated with said driving drums and means for simultaneously starting right hand tension in one spring and left hand tension in the other spring.

30. 16. In a traffic signal, a shaft, a light cylinder mounted on said shaft, reversely arranged springs between said shaft and light cylinder, one of said springs being under right hand tension, the other spring being under left hand tension and means 40 for alternately increasing the tension of said springs and thereby cause the light cylinder to make a partial movement at the end of each cycle.

35. 17. In a traffic signal, the combination with a housing, of a light cylinder mounted to rotate on a vertical axis within said housing, said cylinder having oppositely disposed transparent distinctively colored windows, means including a motor and reversely disposed springs for imparting intermittent reverse rotary motion to said cylinder, means for engaging and holding said cylinder while same is at rest, an indicator ring surrounding said cylinder, means for reciprocating said ring lengthwise of said cylinder and its windows and a source of light within said cylinder.

45. 18. The combination as set forth in claim 17 and the windows of said cylinder being provided on their sides with longitudinally spaced lateral extensions which cooperate with the indicator ring in providing time warning signals.

50. 19. The combination as set forth in claim 18 and a source of light within said cylinder.

55. 20. The combination as set forth in claim 18 and reflectors carried by said ring for directing light rays outwardly therefrom.

HERBERT B. MUELLER.
